INVENTOR.
GEORGE KARP
BY *Richard G. Geist*
ATTORNEYS

UNITED STATES PATENT OFFICE.

GEORGE KARP, OF LONG ISLAND CITY, NEW YORK.

DISAPPEARING-TELEPHONE TABLE.

Application filed April 20, 1923. Serial No. 623,351.

To all whom it may concern:

Be it known that I, GEORGE KARP, a citizen of the United States, residing at Long Island City, county of Queens, and State 5 of New York, have invented certain new and useful Improvements in Disappearing-Telephone Tables, of which the following is a specification.

The principal object of this invention is 10 to provide a new and improved construction in a telephone table having a compartment therein to receive the telephonic transmitting and receiving apparatus and a movable platform mounted in said compartment 15 upon which the apparatus is placed connected with a hinged top or closure in such a manner that the apparatus will disappear into the compartment when the top is closed and will be withdrawn therefrom 20 when the top is opened.

Another object is to so provide means upon the platform to securely hold the telephone thereto and to provide a simple construction, which can be easily manipulated 25 and which can be manufactured and sold at a comparatively low price.

For the accomplishment of these and such further objects as will hereinafter be apparent to those skilled in the art to which 30 this appertains, the invention consists in the construction, combination and arrangement of parts herein specifically described and illustrated in the accompanying drawings, wherein is shown a preferred embodiment of 35 the invention, but it is to be understood that changes, variations and modifications may be resorted to which fall within the scope of the claim hereunto appended.

In the drawings forming a portion of this 40 specification:

Fig. 1 is a front view of an improved table embodying my invention parts being shown in section.

Fig. 2 is a top or plan view of the structure shown in Fig. 1, the hinged top being 45 broken away.

Fig. 3 is a central section through the telephone receiving compartment showing the lid closed and the telephone entirely 50 encased within the table.

Fig. 4 is a view similar to Fig. 3 showing the lid open with the telephone withdrawn and in position for use and

55 Fig. 5 is a detail of the top supporting means.

As shown in the drawings, the table 10

is provided with legs 11 and the upper or body portion comprises a cabinet having an open front compartment 12 for holding the telephone directories, and an open topped compartment 13 for enclosing the telephone, the front of which is closed by the panel 14. A hinged drop board 15 is preferably provided at the front of the table to act as retaining means for the directories and also 60 to give a better appearance.

A framing extends around the top of the table and consists of the side boards 16 and 17 and front and rear boards 18 and 19 respectively.

Extending between the front and rear boards 18 and 19 is a strip 20 which rests upon the partition 21 which divides the telephone compartment from the book compartment. A panel 22 is secured upon the 70 under faces of the side board to provide a depressed pocket for the reception of a memo pad and pencil, the panel 22 preferably being provided with a groove 23 to receive the pencil.

Suitably secured within and extending vertically from the top to the bottom of the compartment 13 are a pair of guide rods 24 about which are slidably engaged the grooves 25 provided in a horizontally extending platform 26. The lower ends of connecting links 27 are pivotally secured to the central portions of the sides of the platform 26 at the base of the grooves 25, the upper ends of the links being pivotally secured to the ends of a cleat 28 secured to the under face of the hinged top or closure 29.

An articulated stop is provided to hold the top 29 in the open position shown in 95 Fig. 4 and consists of the members 30 and 31, the outer ends of which are pivotally connected as at 32 and 33 to the top 29 and side board 16 respectively, while the inner juxtaposed ends of the members 30 and 31 are pivotally connected together as at 34. The member 31 is slotted as at 35 to cooperate with the pin 36 and act as a stop in the manner common to devices of this 100 character.

The side board 16 is cut away as indicated at 37 (Fig. 2) to provide a clearance for the members 30 and 31, when the top 29 is in the closed position shown in Fig. 3.

A hinged door 38 is preferably provided 110 at the rear of the telephone compartment to permit the phone to be placed within the

table, a small notch 39 being cut in the bottom of the door to permit the passage of the telephone wires 40, and a similar groove 41 is cut in the back edge of the platform 5 for the same purpose.

Means are provided for securing the telephone to the movable platform and comprises the rectangular shaped cleat 42 divided into two parts along the line 43, and 10 secured by the screws 44 to the platform. The cleat 42 is provided with an aperture 45 and its under face is cut out as at 46 to receive the base of the phone, the aperture 45 and cut out portion 46 being located to 15 one side of the platform as clearly shown in Fig. 2 to allow for the telephone receiver.

The operation of the device is as follows, assuming the platform 26 to be in its lower position shown in Figs. 1 to 3, the rear door 20 38 is opened and the telephone is inserted into the compartment 13 and placed upon the platform, the front portion of the cleat 42 being removed. The top 29 is then raised causing the links 27 to raise the platform, 25 the vertical guide rods 24 cooperating with the grooves 25 to hold the platform in a horizontal position during its raising movement. When the top 29 is thrown back to the position shown in Fig. 4 the members 30 30 and 31 will move slightly past dead center, the pin 35 and slot 36 cooperating to limit the movement of the top. The pivotal connection of the links 27 will permit the platform 26 to retain its horizontal position 35 during its vertical movements and it will be noted that as the points of connection of the links 27 are on a central line of the platform there will be no tendency of the platform to tilt and bind upon the guide 40 rods 24.

After the platform has been raised to its upper position the front section of the cleat 42 is secured in place and the table is then

in condition for continued use. To lower the telephone into its compartment the 45 locked joint of the members 30 and 31 is broken and the top 29 swung to its closed position, the platform 26 and phone thereon disappearing into the compartment 13 and the table then presenting the appearance of 50 an ordinary table.

It will be obvious that the shape or appearance of the table may be varied as desired.

Having thus described my invention, 55 what I claim as new and desire to secure by Letters Patent is:

A device of the character described, including a table having an open topped compartment, a pivotally mounted closure 60 adapted to close the top of said compartment, a pair of vertically extending guide rods centrally mounted in the sides of said compartment, a horizontally extending platform having a pair of grooves therein for 65 receiving said guide rods, pivot pins fixed to the central portions of the sides of said platform contiguous to said grooves, links pivotally connected to said pins and said closure to cause said platform to be raised 70 out of or lowered into said compartment when said closure is moved from closed to open position or vice versa, said grooves and guide rods cooperating to hold said platform in a horizontal position during 75 its vertical movement, and stop members pivotally connected at their outer ends to said closure and to the main frame of said table respectively, and at their inner ends pivotally connected to each other, to stop the movement of said platform and closure when said platform is raised to the top of 80 said compartment.

In testimony whereof I have affixed my signature.

GEORGE KARP.
